CAN OPENER

Courtland N. Smith, Jr., Colonia, N. J., assignor
to The Regina Corporation, Rahway, N. J., a
corporation of New Jersey

Application February 16, 1945, Serial No. 578,232

6 Claims. (Cl. 30—9)

1

The invention relates to a can opener and more particularly to that type of can opener which utilizes a rotary cutting disc and a rotat-
ing feeding device for engaging the flange of the can and by means of which the can is propelled during engagement with the cutting disc. Can openers of this type are adapted to remove the top of the can by severing the top at a point ad-
jacent its periphery.

More particularly, the invention relates to a novel construction of such can opener in which there is provided a spring guide for effecting the proper positioning of the top flange of the can in relation to the rotary cutting disc and to maintain the can in proper position for severing the top of the can as the can is rotated by the feeding device.

Among the objects of the invention is to provide such spring guide construction which properly positions the can to be opened in relation to the rotary cutting disc and the rotating feeding device when the can is loaded in the can opener, i. e. when the can is applied to the device to effect the operation of opening the can.

A further object of the invention is to pro-
vide such a spring guide which is effective to hold the can in proper location with respect to the cutting disc when the top of the can is punc-
tured to start the severing of such can top.

A further object of the invention is to provide such a spring guide which will exert a proper guiding pressure on the can irrespective of the wall thickness of the can, or the thickness of the seam.

A still further object of the invention is to provide such spring guide which will constitute an effective shield against bits of paper torn from the can wrapper, or any bits of food from the can as it is punctured or rotated in the course of removing its top, from working back into the can opener parts.

A still further object of the invention is to pro-
vide such a spring guide of such shape and con-
figuration that it includes two front contact points spaced at the same distance from the face of the rotating feeding device, which contact points exert sufficient pressure when the can revolves to compensate for the natural tendency of the can to work forwardly and away from the proper cutting position. The shape and configuration of the spring guide is also such that it is effec-
tive to press the can outwardly above the point where the rotary cutting disc and rotating feed-
ing device grip the can, thus counteracting the tendency of the can to tilt away from the vertical

2

and thereby insure the cutting of the can top close to the inside wall of the can, as when making the original puncture.

Further and other objects of the invention will appear to those skilled in the art from the following description of a specific embodiment of my invention and as illustrated in the accompany-
ing drawings.

The present invention, in the provision of the spring guide, provides an extremely simple and efficient substitute for the more complicated, structurally as well as operatively, mechanism provided in can openers of this general type as described and illustrated in the patents to Leo Olschewski Nos. 1,999,370 dated April 30, 1935 and 2,278,371 dated April 7, 1942. In such patents, there is disclosed and illustrated a construction of spring controlled pressure rollers for position-
ing and maintaining in such position, the can to be opened in relation to the rotary cutting disc and rotating feeding device. The novel spring guide means of the present invention is in all respects as efficient in operation as the complicated spring controlled pressure rollers of the aforesaid Olschewski patents, and in certain re-
spects exhibits certain advantages over the prior art construction, aside from the great saving effected in materials and construction costs.

In the drawings, in which a specific embodiment of my invention is illustrated, Fig. 1 is a plan view of the can opener constructed in accordance with my invention, showing the same as the can to be opened is applied thereto; Fig. 2 is a similar plan view with the can to be opened in loaded position, and showing the can opener elements when the can is ready for its rotary movement by the feeding device; Fig. 3 is a front view of the can opener with the loading lever and the can being opened partly in section; Fig. 4 is a side view showing the spring guide element in position in relation to the rotary cutting disc and rotating feeding device; Fig. 5 is a plan view of the spring guide element by itself; and Fig. 6 is a side view of such spring guide element.

Referring more particularly to the drawings, in which similar reference characters identify similar parts in the several views, the can opener is constructed for mounting on a wall or other vertical support by means of a mounting bracket 10 which is shown partly broken away. At the forward end thereof, such mounting bracket is formed with an enlargement 13 extending at right angles thereto and being hollow for a purpose later to be described. The enlargement has an inner wall portion 11 extending upwardly and an

outer wall portion 12 likewise extending upwardly forming a channel with the transverse portion 13 as a bottom. A pin 14 passing between the vertically extending enlargement portions 11 and 12 and over the portion 13 pivotally mounts a housing 15 for limited vertical oscillatory movement relative to the bracket.

Extending through the housing 15 is a shaft 16 including an enlarged portion 17.

A head 18 on the forward end of the shaft 16 has its forward face 20 inclined, and against said face is secured a rotary cutter element 21. The cutter element 21 is mounted to rotate relative to the shaft and is secured in place by a headed fastener 22. The cutter 21 includes a portion 23 arranged substantially vertically when the cutter is in use and located against the inner surface of the upper end flange of the can, the head of which is to be removed. Such cutter also includes a rear cone surface 24 located substantially horizontally when the device is being used and engaging the upper edge of the flange of the can being operated upon. It will be noted that the cutter 21 rotates on the screw 22 and is inclined at an angle from the horizontal, with a front cutting portion having a conical rear surface. The angle between the rear surface of the cutter and the center of its axis being substantially the same as the angle of inclination of the cutter from the horizontal; the lower rear element of the cutter, when in use, is in a vertical position where it is in contact with the can rim.

Adjacent the housing 15 is a pair of cam surfaces 25 and 26 located directly opposite one another, the former being the end surface of the support for housing 15, and the latter the end surface of a sleeve 27. A nut 28 threaded onto the rear end of the shaft 16 secures the sleeve 27 upon the shaft for turning movements thereon. Secured to or formed with the inner end portion of the sleeve 27 is a lever or handle 30 adapted for manual manipulation to impart an oscillatory or turning movement to the sleeve.

On its outer end, the hollow extension 13 is laterally expanded to provide a ledge portion 31. A strap 32 has one end secured to the ledge 31 as by a pin 33, and such strap extends across and rearwardly of the ledge 31 below the outer end of the sleeve 27, and has its other end 34 pass beneath a bridge-like piece 35, whereby upward movement of such end of the strap under the influence of the coil spring in the piece 35 is limited. The strap 32 has its intermediate portion bent upwardly as shown at 36, providing a cam surface for engagement by the cam element 29.

Mounted in and extending through the hollow extension or enlargement 13, is a shaft 37. On the forward end of the shaft 37 is the propelling or rotating feeding device for rotating the can, the head of which is to be removed. Such propelling means or rotating feeding device comprises a wheel 38 toothed about its periphery.

At the opposite end thereof, the shaft 37 is provided with the crank or handle 39 which is adapted to be manually rotated to cause rotation of the shaft 37 and, therefore, of the propelling wheel 38.

The bearing for the shaft 37 rearwardly of the cutting wheel 38 is formed integrally with the transverse extension 13 of the mounting bracket, the bearing 40 having an interior tubular cavity 41 in which, and surrounding the forward end of the shaft 37, is mounted a coil spring 42. Such coil spring exerts pressure forwardly against the rear face of the spring guide element 43 posi-

tioned between such coil spring and the propelling wheel 38. The bearing 40, as shown particularly in Figs. 3 and 4, has a horizontal guide extension 44 which is part of the can opener frame and extends forwardly under the propelling wheel 38 and provides a ledge for the forwardly bent lower edge of the spring guide element, preventing such spring guide element from revolving by reason of its snug rest upon such guide extension. While such spring element 43 is thus prevented from revolving, it is completely free to move inwardly and outwardly along the axis of the propelling wheel shaft 37.

The spring guide element 43, shown in front and side view in Figs. 5 and 6, is of a particular shape and configuration. It is made of thin sheet metal having a central aperture 45 by means of which it is mounted upon the shaft 37 rearwardly of the propelling wheel 38 and forwardly of the coil spring 42, the lower edge 46 of such spring guide element being flat and turned forwardly as shown in Fig. 6 to rest snugly against the guide extension 44. The upper edge of the spring guide element is arcuately hollowed as 47 to clear the rear conical surface of the cutter. The spring guide element is formed with two side contact surfaces or wings 48 and 49 which are turned slightly backwardly as shown at Fig. 6 and are the same distance from the propelling wheel face thus guiding the loading of the can to be operated upon in its proper position for puncturing. The can is guided to proper puncturing position by placing the upper edge thereof in contact with the surfaces 48 and 49 of the spring guide element, and moving it upwardly until the top edge of the can abuts the lower surface of the arm 50 extending from the can opener frame.

In the operation of the can opener to remove the top of a can by severing such top at a point adjacent its periphery, the can to be opened, as the can 51, is placed with its upper end portion against the contact surfaces 48 and 49 of the spring guide element 43, by inserting its flange between the surfaces 23 and 24 of the cutter 21 and moving the can upwardly until it abuts the lower surface of the arm 50. Holding the can 51 against the cutter and against the contact surfaces 48 and 49 of the spring guide element, the lever 30 is swung forwardly, imparting a rotary movement to the sleeve 27. As the sleeve is turned, the cam surfaces 25 and 26 on the housing 15 are operative to cause the sleeve 27 to move toward the right in Figs. 2 and 3, and being connected to act against the nut 28 on the shaft 16, the latter is moved with the sleeve, drawing the cutter 21 toward and against the inner side of the cam flange, as shown in Fig. 3.

As the sleeve is turned in the manner indicated, the cam 29 is carried with it and also turns with the sleeve. As the sleeve turns, the said cam 29 rides onto the cam surface or raised portion 36 of the strap 32 and slightly tilts the housing 15 on the pin 14 to lower the cutter toward or against the head of the can 51. As the sleeve reaches the limit of its movement toward the right, the high portion of the cam 29 rides onto the raised portion or cam 36 and causes a substantial tilt of the housing 15, whereby the cutter is lowered to the inner side of the can flange and is forced through the can so as to pierce the can head. These movements of the cutter 21 draw the can flange against the teeth of the wheel 38 and also against the contact surfaces 48 and 49 of the spring guide element 43. During this motion of the cutter, its portion 24 engages the upper edge

of the flange of the can and causes the lower edge of the flange to totally engage the teeth of the wheel 38 of the can propelling means. Now the can is clamped in place by the cutter ready for the operation of cutting out its head or top.

Such cutting out operation is effected by the rotation of the handle 39. This operation of removing the can head by the rotation of the handle 39 is known to those skilled in the art.

The coil spring 42 mounted within the bearing of shaft 37 will yield to the pressure of the wheel 38 when the can is pressed against the wheel and thus the opener is adapted to receive cans having flanges of different thicknesses. It will also automatically adjust itself to variations in the thickness of the walls and the seam of the can during the feeding and cutting operation, so as to insure a uniform and effective gripping and feeding of the flange under all conditions.

The coil spring 42 is prevented from revolving by the spring guide element 43 by presenting a stationary contact surface therefor.

As stated hereinabove, the can opener will operate on cans of different diameter or shape, as the spring guide element is effective to guide the can with proportionate pressure on the two contact surfaces 48 and 49, regardless of the diameter or shape of the can. The guiding pressure on the can is not affected even by excess wall thickness of the can or the pronounced seam of the conventional can as the spring guide moves with the propelling wheel, the latter compensating for different wall thicknesses of a can wall, and of heavy seams by means of the coil spring positioned rearwardly of the propelling wheel.

It is known to those skilled in the art of can openers that there is a natural tendency of the can to work forwardly and away from the proper position of the opener when operated upon by this type of can opener. The novel spring guide element provided in my can opener overcomes this difficulty as the front contact surfaces thereof exert more pressure when the can revolves than when the can is loaded and is being punctured. The pressure exerted by the spring guide element upon the can during the puncturing operation is, however, sufficient to insure that the cutter will puncture the can top close to the inside wall of the can. It is also known to those skilled in the art that the can during the operation of cutting out its top, has a tendency to tilt away from the vertical. My novel spring guide element, by reason of its shape and configuration overcomes this difficulty also, as it presses outwardly above the point where the cutter and propelling wheel grip the can.

Various other advantages not herein specifically recited will be evident to those skilled in the art from the detailed description hereinabove.

I claim:

1. A can opener including a revolvable cutter and a can feeding means comprising a propelling wheel engaging the exterior of the can to propel the same in relation to the cutter, said revolvable cutter having a substantially horizontal part engaging the top of the can rim while the propelling wheel is rotated and is in frictional engagement with the bottom of the can rim, a guide element for positioning the can in the opener, comprising a substantially flat spring metal body mounted rearwardly of and adjacent the can propelling wheel and beneath the revolvable cutter and having a pair of forwardly extending wing elements

disposed at each side of the point of cutting of said cutter.

2. A can opener including a frame, a revolvable cutter, a can feeding means comprising a propelling wheel engaging the exterior of the can to propel the same in relation to the cutter, said revolvable cutter having a substantially horizontal part engaging the top of the can rim while the propelling wheel is rotated and is in frictional engagement with the bottom of the can rim, a guide extension on said frame below said can propelling wheel, and a guide element for positioning the can in the opener, comprising a flat spring metal body mounted rearwardly of the can propelling wheel and beneath the revolvable cutter and having a pair of forwardly extending wing elements disposed before and behind the point of cutting of said cutter, the lower edge of said spring metal body being seated upon said extension from the can opener body.

3. A can opener including a revolvable cutter adapted to be positioned within the end flange of a can and to cut the end wall of the can adjacent the can flange, can feeding means comprising a propelling wheel engaging the exterior of the can to propel the same in relation to the cutter, said revolvable cutter having a substantially horizontal part engaging the top of the can rim while the propelling wheel is rotated and is in frictional engagement with the bottom of the can rim, and means for engaging the flange of the can from the exterior thereof, to cooperate in holding the can flange adjacent said cutter during the cutting operation, said means comprising a flat spring metal body disposed below and in such proximity to the revolvable cutter as to engage the exterior of the can flange while the cutter engages the interior of the can flange, and having two flange contact surfaces, one engaging the flange of the can forwardly of the point of cutting of said cutter and one engaging the flange of the can rearwardly of said point of cutting.

4. A can opener including a revolvable cutter adapted to be positioned within the end flange of a can and to cut the end wall of the can adjacent the can flange, a can feeding device adapted to rotate the can and engaging the exterior of the can to propel the same in relation to the cutter, said revolvable cutter having a substantially horizontal part engaging the top of the can rim while the propelling wheel is rotated and is in frictional engagement with the bottom of the can rim, and means for engaging the flange of the can from the exterior thereof, to cooperate in holding the can flange adjacent said cutter during the cutting operation, said means comprising a flat deformable metal body disposed rearwardly and below the can feeding device and in such proximity to the revolvable cutter as to engage the exterior of the can flange while the cutter engages the interior of the can flange, and having two flange contact surfaces straddling the can flange at the point of cutting of said cutter.

5. A can opener including a revolvable cutter adapted to be positioned within the end flange of a can and to cut the end wall of the can adjacent the can flange, a rotating can feeding wheel for engaging the flange of the can to propel the can in relation to the cutter, said revolvable cutter having a substantially horizontal part engaging the top of the can rim while the propelling wheel is rotated and is in frictional engagement with the bottom of the can rim, and means for engaging the flange of the can from the exterior thereof

against the can flange both before and behind the point of cutting of said cutter, and both during the loading and rotation of said can. In a can opener including a cutter adapted to be positioned within the end flange of a can and to cut the end wall of the can adjacent the can flange, said revolvable cutter having a substantially horizontal part engaging the top of the can rim while the propelling wheel is rotated and is in frictional engagement with the bottom of the can rim, means for engaging the flange of the can from the exterior thereof, to cooperate in holding the can flange adjacent said cutter during the cutting operation, said means comprising a flat spring metal body disposed below the cutter and having two flange contact surfaces, one engaging the flange of the can forwardly of said cutter and the other rearwardly thereof.

flat spring metal body disposed below the cutter and having two flange contact surfaces, one engaging the flange of the can forwardly of said cutter and the other rearwardly thereof.
